Primary Examiner — Melanie Pellegrini*(74) Attorney, Agent, or Firm* — Fross Zelnick Lehrman & Zissu P.C.; Charles T. J. Weigell, Esq.; Lawrence E. Apolzon, Esq.(57) CLAIM

The ornamental design for a jewelry item, as shown and described.

DESCRIPTION

FIG. 1 is a front perspective view of a jewelry item showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting gemstones, gem settings and unclaimed portions of the jewelry item form no part of the claimed design.
